UNITED STATES PATENT OFFICE.

ULRICH FRIEDEMANN, OF HACKNEY, LONDON, AND THOMAS E. THOMPSON, OF LONDON,
ENGLAND.

IRRIGATOR FOR MEDICAL, CHEMICAL, AND OTHER PURPOSES.

1,289,723.

Specification of Letters Patent. Patented Dec. 31, 1918.

Application filed July 29, 1916. Serial No. 112,188.

To all whom it may concern:

Be it known that we, ULRICH FRIEDEMANN and THOMAS EDMUND THOMPSON, residing at 57 Navarino road, Hackney, London, 5 N. E., England, and 121 Rosebery avenue, London, E. C., England, respectively, have invented certain new and useful Improvements in or Relating to Irrigators for Medical, Chemical, and other Purposes; and we 10 do hereby declare the following to be a full, clear, and exact description of the invention, such as will enable others skilled in the art to which it appertains to make and use the same.

15 This invention relates to improvements in irrigators for medical, chemical and other purposes of the type in which the liquid is drawn up from a container or receptacle by means of an apparatus which when im- 20 mersed in the liquid allows the latter to compress air contained in the apparatus and by a siphon like action to start the flow of the liquid through the apparatus, which flow continues so long as the apparatus is in the 25 liquid and until the container is emptied.

Apparatus of this kind has heretofore been constructed as a single element of glass or the like, the parts being sealed or permanently connected together and consisting of 30 a central tube open at the bottom and the top with a bulb or casing surrounding it and sealed to it at each end. From the top of the bulb or casing and forming a continuation of the central tube is an extension to 35 which a rubber or like tube connected to a nozzle or the like is attached. A small bag- like receptacle or pocket is formed on the side of the extension for the purpose of containing when desired a pellet or tablet of 40 medicament. A hole is formed at the bottom of the bulb or casing and another hole is formed in the inner central tube near its upper end inside the bulb.

45 In the apparatus as above described considerable difficulties have been experienced in cleansing the interior owing to its construction in a non-separable single piece, and it is the object of the present invention to construct an improved apparatus of the kind referred to which may be easily taken to 50 pieces for the purpose of cleansing and readily assembled again in an airtight manner.

The invention will now be described in

connection with the accompanying drawings 55 in which:—

Figure 1. is a sectional elevation of the improved device, and

Fig. 2. is a similar view of a modified form. 60

The bulb or casing may be made of aluminium, glass or other suitable material and in the form shown in Fig. 1 the bulb is formed with top and bottom pieces *a* and *b* internally threaded at *c* and *d* to engage 65 threaded portions on a central tube *e* of metal, glass or the like. The central tube *e* extends through the top piece *a* and is formed with an enlargement *f* for securing it to a rubber or like tube. It is also pro- 70 vided with a screwed opening *g* at its side between its upper end and the top piece *a* for detachably securing a bag-like receptacle for containing the pellet of medicament. The top and bottom pieces *a* and *b* 75 are recessed as shown at *h* to engage the ends of a cylinder *i* preferably of glass, forming the body of the bulb, a rubber or like washer or packing *j* being inserted in each recess for the ends of the cylinder *i* to bear against to 80 form an airtight joint.

In assembling the parts, the top piece *a* is first placed on the central tube *e* and screwed on to the upper enlarged screwed portion thereon, a rubber or other suitable 85 joint being used if desired. The glass cylinder *i* is then passed over the central tube *e*, and its upper end inserted in the recess *h* in the top piece *a* against the packing *j* therein. The bottom piece *b* is next screwed 90 on to the lower screwed portion of the central tube *e* which is of slightly smaller diameter than the upper screwed portion to allow the top piece *a* to pass over it, and is provided with suitable packing if required. 95 The lower end of the glass cylinder *i* is inserted in the recess *h* in the bottom piece *b* and when the latter is screwed up all the parts are secured in an airtight manner.

The bottom piece *b* is perforated at *k* and 100 the central tube *e* is provided with a hole *l* in the usual manner.

In the modified form shown in Fig. 2 the top piece is formed in one with the central tube *e* and with the cylinder *i*, the bottom 105 piece *b* being secured to the latter in the manner above described. In this case the entire apparatus with the exception of the

bottom piece *b* is preferably made of glass, and a branch piece *m* closed by a metal cap *n* is provided for the purpose of containing the pellet of medicament. Instead of the 5 joint shown between the bottom piece and the cylinder, a screw threaded joint may be employed or the parts may be secured together by means of screwed metal or other unions engaging beads or flanges formed on the pieces, a packing ring being inserted 10 between the beads.

It is to be noted that in the construction shown in Fig. 2 the joint between the bottom piece *b* and the upper part of the device may 15 be situated at any convenient point in the length thereof, for instance it may coincide with the position of the joint between the cylindrical member *i* and the top piece *a* in Fig. 1.

20 When the central tube *e* or the bulb is made of opaque material a glass or other transparent tube may be inserted in the rubber tube leading to the nozzle or the like in order that the flow of liquid through the apparatus may be observed.

In operation the apparatus is immersed in the liquid so that the latter is above the enlargement *F*, while the liquid container is placed in a position higher than that at 30 which the nozzle has to be used. Liquid rises in the central tube *e* to a level equal to that in the receptacle and also enters the bulb or casing through the perforation *k* in the bottom piece *b*. Liquid entering the latter compresses the air in the bulb or casing and owing to the head of liquid existing in the container the air is eventually forced out 35 through the hole *l* causing the liquid above it to pass farther toward the nozzle while fresh liquid rises to take its place.

40 By this means siphonic action may be started and the whole of the liquid be eventually withdrawn from the container, up the central tube *e*, past the medicament which it absorbs, and through the tube to be discharged through any suitable form of nozzle.

When the apparatus is to be used for chemical purposes, for example in emptying bottles or other receptacles containing acid 50 or other liquid giving off deleterious fumes, the small bag-like receptacle above referred to need not if desired be provided.

It will be understood that the parts of the apparatus may be made from any suitable 55 material according to the purpose for which the irrigator is required and that the invention is not limited to the constructions above described, the essential feature of the in-

vention being that the parts are made separable for cleansing purposes as distinguished 60 from known types of apparatus of this type which, as above stated, have heretofore always been formed of a single element.

We claim:—

1. An irrigator, comprising a starter for 65 a siphon, consisting of a cylinder, a central tube formed with screw threads at its upper and lower ends, top and bottom cups each provided with an internally screw threaded opening adapted to embrace the first named 70 screw threads, said cups being capable of retaining between them the said cylinder.

2. An irrigator comprising a starter for a siphon, consisting of a cylinder, a central tube, top and bottom cups adapted to embrace 75 said tube and being capable of retaining between them said cylinder, said tube being provided with a recess formed above the upper of said cups for the reception of a medicated pellet.

80 3. An irrigator, comprising a starter for a siphon, consisting of a cylinder whose edges are formed with shoulders, a central tube formed with screw threads at its upper and lower ends, top and bottom cups each 85 provided with an internally screw threaded opening adapted to embrace the first named screw threads, the outer edges of the cup members being formed with a shoulder adapted to engage the shoulders formed on 90 the edges of the cylinder, whereby to retain the cylinder between them and suitable packing interposed between the edges of the cups and the cylinder.

4. An irrigator comprising a starter for a 95 siphon including a tube, a cylinder adapted to envelop such tube and being connected at its upper end thereto, a cup-shaped member provided with an opening through its bottom adapted to be positioned so that the tube 100 projects through such opening, the upper edge of said cup engaging the lowermost edge of the cylinder so that an airtight joint is formed, the cup-shaped-member being provided with a second small opening near 105 its base, the tube being provided with an opening formed below the point of engagement of the cylinder with the tube adjacent the upper end of the former.
